MOBILE POWER GENERATING UNIT

Jerome I. Davis, Bedford, N. Y., assignor to Consolidated
Diesel Electric Corporation, Stamford, Conn., a corporation of New York

Application May 2, 1956, Serial No. 41,308

Term of patent 14 years

(Cl. D14—3)

Fig. 3.

Fig. 4.

Fig. 5.

Fig. 1 is a left side elevational view of a mobile power generating unit showing my new design;
Fig. 2 is a right side elevational view;
Fig. 3 is a front elevational view;
Fig. 4 is a rear elevational view; and
Fig. 5 is a top plan view.

I claim:

The ornamental design for a mobile power generating unit, substantially as shown.
